UNITED STATES PATENT OFFICE

2,069,596

METHOD OF TREATING OIL

Albrecht von Groeling, Los Angeles, Calif.

Application January 29, 1930, Serial No. 424,254

1 Claim. (Cl. 196—62)

This invention relates to a method and means whereby fuel oil may be treated in such a manner as to produce the more valuable hydrocarbon products.

More particularly, the invention has for an object the provision of a method and means which is adapted for cooperation with any type of topping or cracking plant such as for example described in my Patent 1,295,088 and which said invention may utilize the residue oil from said cracking or topping plant to convert said residue oil into higher and more valuable hydrocarbons.

The invention is particularly adaptable to treat residues having free carbon or asphalt which is to be either removed or converted.

Another object is the novel arrangement of various apparatus whereby a cracking of crude oil may be taking place and the residue or un-cracked part thereof at the same time utilized in a continuous and circulatory system in such a manner as to be combined with other gases to in turn produce more valuable hydrocarbons.

Another object of this invention is to utilize a series of units in such a manner as to first crack a crude oil and produce a residue, which residue is to in turn be so treated as to turn said residue into valuable hydrocarbon products, to the end that all of said residue is utilized and no waste product or substantially no waste product or residue remains after the several steps in the operation of the apparatus are completed.

Another object is the utilization in certain embodiments of what may be termed a continuous cracking process, the second phase cracker linking the first phase cracker.

Another object of the invention is the provision of a system and means whereby free hydrocarbon can be segregated and in such a manner that the carbon can be converted into light compounds.

As a brief statement of the invention, it may be said that after the usual fractionation or topping has taken place from the crude oil, to the end that the light weight constituents are abstracted, the residue is treated to produce synthetic gasoline, including heavy naphtha, some kerosene, fuel oil, coke or asphalt. The first refining process of the said crude will, of course, produce various values such as gasoline, kerosene, and gas oil. These products the present invention is not particularly interested in. It is in the treating of the residue of the crude after the removal of these products by the first cracking operation that this invention is primarily directed. The second cracking plant is adapted to

treat the residue under high temperature and pressure and which temperature and pressure is gradually reduced but not before the residue under high heat and pressure is acted upon by some fluid injected into the same which combines with said residue, whereby the normally un-cracked residue which may contain asphalt, and possibly paraffin wax, are converted into light weight hydrocarbons. More especially, the carbon is segregated and converted into hydrocarbon compounds, which will tend to produce oil out of coke or coal. If natural gases of the paraffin series are used, they are transformed into unsaturates in combining with nascent carbon when set free.

Other objects of the invention will be set forth as the description of the invention proceeds.

The drawing is a side elevation, partly diagrammatic and partly in section, of apparatus which may be utilized in carrying out the invention.

Referring to the drawing, I have shown for the purpose of illustration a topping or cracking plant at A, which includes a heater a, a dephlegmator or still b, further dephlegmators c at 1 and 2, a preheater d, an expander e, and one or more coolers and tanks f as shown at 3, 4, 5, and 6. These series of units may be utilized in cracking a crude oil to derive therefrom various fractions of hydrocarbon such as gasoline, kerosene and the like, and such units in combination represent one form of cracking or topping plant which performs very efficiently the several operations, although within the scope of the present invention, other types of cracking or topping plants may be as readily utilized.

The cracking or topping plant A is adapted to act in conjunction with means B. The means B is adapted to treat the residue oil from the cracking or topping plant A to produce further valuable hydrocarbon products. More particularly, the means B includes a heater g, temperature and pressure reducers h, of which there may be a series, as shown at 7, 8 and 9, a dephlegmator j, and coolers and tanks k, as shown at 10, 11, 12 and 13. The cooler and tank unit shown at 14 may operate in conjunction with either the cracking and topping plant A or with the means B for treating the fuel oil. Included in the means B are one or more pumps m and n.

The cracking and topping plant A will be first described, followed by a description of the means B for treating the residue or fuel oil after the crude has been cracked by the plant A.

The preheater d includes a tank 15 within

which is a pipe coil 16 located near the bottom of said tank. A pipe 17 is received within said tank and has its mouth portion adjacent the bottom of the tank. A further pipe 18 has the mouth portion thereof above the pipe coil 16 and leads from said tank. The tank is provided with a dome 19. A pipe communicates between said dome and the cooler unit *f* shown at 3, which cooler unit includes the cooler proper and a tank 10 for receiving the condensed fluid. The pipe 18 is in direct communication with the dephlegmating preheater *c*, shown at 2. This type of dephlegmating preheater includes a tank 20 and a jacket member 21 surrounding the same. The tank 20 is conventional in form, including the usual baffle plates to cause gases to pass therein in a devious path. The jacket is closed at both the top and bottom and does not entirely surround the tank 20 but may be spaced above the bottom portion thereof, as shown in the drawing. The pipe 18 communicates, as before stated, with the space included between the jacket and the periphery of the tank 20 and adjacent the top of said tank and jacket, as shown at 22. A further pipe 23 has its mouth portion adjacent the bottom 24 of the jacket and this pipe 23 in turn communicates with the preheating dephlegmator *c* shown at 1 in the same manner as for the dephlegmating preheater shown at 2, both dephlegmating preheaters being identically constructed. A pipe 25 leads from the jacket of the dephlegmating preheater shown at 1 to the still or dephlegmator *b*. This pipe terminates with one or more spray nozzles 26 positioned adjacent the top of the dephlegmator or still *b*. This still or dephlegmator *b* includes a casing 27 provided with a dome portion 28. A pipe 29 communicates with the dome 30 of the expander *e*. This expander is of conventional construction and for this reason not detailed. The still *b* has a valved connection with a pipe 31, which in turn has valved connection 32 with a pump *o*. A pipe 33 communicates with the pipe 32 and through a valved connection 34 with the heater *a*. The expander *e* has communication through a valved pipe 35 with the heater *a*. The pump *o* communicates through a valved pipe 36 with a dehydration unit *p* of conventional construction, and a pipe 37 leads from said unit past a valve 38 to the pipe 33. Likewise said pump *o* is connected by a pipe 36a to pipe 33. A pipe 39 communicates with the top of the dome 28 and the bottom of the dephlegmator casing or cylinder 20 of the dephlegmating preheater *c* shown at 1, and a pipe 40 communicates with the top of the cylinder 20 of the unit shown at 1 and with the bottom of the cylinder 20 of the unit shown at 2. A pipe 41 is in communication with the top of the cylinder 20 of the unit 2 and one of the cooling units *f* shown at 4. The bottom of the tank 20 of the unit shown at 2 is in communication with the still *b* through the medium of a pipe 42, which includes valves 43 and 44, the valve 43 being near the outlet of the tank and the valve 44 adjacent the still. A further pipe 45 provided with a valve 46 communicates with a further cooling unit *f* shown at 5. With respect to the dephlegmating preheater shown at 1, a pipe 46 is provided with valves 47 and 48 and allows communication between the bottom of the tank 20 of this particular unit and with the still *b*, and a further pipe 49 provided with a valve 50 communicates with a further cooling unit *f* shown at 6. It will be noted that the valves 43 and 46, 48 and 50 allow any liquid received within the

dephlegmating preheater casings 20 a flow path in one of two directions or, in certain instances, in both directions. The expander *e* has a connection through the medium of a pipe 51 with the coil 16 in the preheater *d* and a valve 52 controls communication between said pipe coil 16 and expander *e*.

The operation of the cracking or topping plant A is undoubtedly clear to those skilled in the art, but by way of explanation, it may be said that crude oil from a source of supply is passed within the preheater tank *d* through the medium of the pipe 17. This crude oil may pass through the pipe 18 into the jackets 21 of the dephlegmating preheaters, thence into the still *b* and through the pipe 33 into the heater *a* or by closing the valve 53 and opening the valve 32, said fluid may be pumped by the means *o* through the dehydrating unit *p* to remove water from the oil, and thence past the valves 38 and 34, the valve 35 being closed, into the heater *a*. Or the residue may be forced directly under pressure into the heater *a* by the pump *o* by closing the valve in pipe 36, closing valve 53, and opening opening valve 32. In actual practice, the heater *a* will be filled or partially filled to a desired level therein with crude oil, as would likewise be the preheater *d*. The preheater *d* is of the low heat pressure type in the present instance and a temperature of perhaps 60° to 80° C. is maintained. However, I do not limit myself to any particular temperature. The heated crude oil from the heater *a* is directed under pressure reduction past the valves 34 and 35 into the expander *e*. The lighter vapors of the crude oil are expanded and received within the dome 30 and said vapors in turn pass through the pipe 29 into the still *b*. The hot residue of the crude would be directed, as to flow, past the valve 52 into the pipe 51 and thence into the coil 16. Here a temperature of 40 from 60° to 80° C. may be maintained. The crude oil within the preheater *d* is heated by the hot oil passed through coil 16 and said oil in turn directed through the pipe 18 into the jacket of the dephlegmating preheater *c*, shown at 2. The 45 hot vapors from the crude oil received within the still *b* in turn are received within the dome 28, and thence conducted by the pipe 39 into the bottom of the tank 20 of the dephlegmating preheater *c* shown at 1. The crude oil which has 50 flowed into the dephlegmating preheater shown at 2 is also conducted through the pipe 23 into the jacket of the dephlegmating preheater shown at 1. This oil is at a lower temperature than the vapors conducted into the tanks 20 and likewise 55 at a lower temperature than the vapors conducted by the pipe 40 from the tank 20 of the unit shown at 1 into the tank 20 for the unit shown at 2. Thus, there is a differential temperature between the oil surrounding the tanks 20 and the 60 vapors therein, with the result that there is a heat exchange therebetween causing a condensation of certain of the vapors. In actual practice, the crude oil from the preheater *d* is injected into the still *b* in the form of a spray through the 65 nozzles 26 and the hot gases within the expander contact with this spray of crude oil and tend to crack or reexpand certain constituents thereof. Thus, vapors within the dephlegmating preheaters that have not condensed may be conducted, 70 for instance, to the cooler unit *f* shown at 4 where condensation takes place and a hydrocarbon having certain properties obtained.

The residue liquid within the tanks 20 of the dephlegmating preheaters may be removed. 75

Thus, by closing the valve 48 of the first unit 1 and opening the valve 50, such residue or condensate may be passed through the pipe 49 and into the cooler units *f* shown at 6. The residue or condensate in the unit shown at 2 may have the valve 43 closed and the valve 46 opened, in which case said liquid is passed through the pipe 45 into the cooler unit *f* shown at 5. If separation of these various fractions is not desired, the valves 46 and 50 may be closed and the valves 43 and 48 opened, in which instance the residues or condensates are conducted by pipes 42 and 46 into the dephlegmator or still *b* where they are acted upon by the hot gases from the expander *e* whereby further extraction of essential hydrocarbon results. As a consequence, a continuing cracking of the oil takes place. Or, if desired, a certain portion of this crude, which does not vaporize, may be passed through the pipe 31 and again forced into the heater *a* through the medium of the pump *o*, together with the fresh oil coming from above. Of course, the pump has always to operate, to the end that a desired pressure may be maintained within the heater *a* while the dehydrator may be eliminated if no water is to be abstracted. It will thus be seen that the oil which is passed from the heater *a*, and which has been expanded in the expander *e* thence passed into the still *b* and from there into the dephlegmating preheaters, is progressively cooled and condensed while the incoming oil from the preheater *d* which is caused to flow within the dephlegmating preheater jackets and which flows in an opposite direction from the movement of the oil from the heater *a*, is progressively heated; this incoming oil from the preheater *d* acting as a condenser for the vaporized crude from the heater *a* and this vapor and condensate from the heater *a* acting to preheat the incoming crude oil from the preheater *d*. Consequently, there is a continuous heat exchange.

It will be noted that a pipe allows communication between the cooler *f* shown at 3 and the dome 19 above the preheater column or casing 15. Thus, the apparatus is so arranged that a rough separation of values from the crude oil within the preheater *d* may be effected by the application of heat at one point only, namely, in the heater *a*, which heat is utilized for preheating the incoming crude oil within the preheater *d* by passing the residue of the crude oil within the expander through the pipe coil 16. The number of dephlegmating preheaters may be varied at will as may likewise the number of coolers *f*.

The means B is utilized for further obtaining valuable hydrocarbon constituents from the residue of the crude oil which have not been dephlegmated, or which have not been extracted by the various dephlegmating preheaters and stored within certain of the cooler tanks *f* from the cracking or topping plant A. For instance, the condensate or residue oil from the expander *e* may be directly passed by means of the pump *n* into the heater *g*, or the hot oil which has been circulated through the pipe 16 may be directed to said heater *g* through the medium of a pipe 54. This pipe is not continuous but broken in that said pipe has included therein valves at 55, 56, 57, 58 and 59. Furthermore, the said pipe includes a cross-head coupling 60, as well as couplings 61, 62, 63, 64, 65 and 66. The pipe 67 from the coil leads to the valve 55 and likewise leads to a valve 68 communicating with a cooler shown at 14. From the coupling 66, the pipe 54

has a connection with the pump *n* and from said pump continues to the heater *g*. This latter pipe, before entering the heater *g*, has interposed therein a valve 69. Temperature and pressure reducers *h* are shown at 7, 8 and 9. These temperature and pressure reducers are conventional in form, the first one shown at 7 being in section, wherein it will be seen that the same includes a casing 70 in communication with a plurality of tubes 71, the tubes in turn communicating with dome 72. Surrounding these tubes is a casing 73 and the construction is such that fluid may be passed around the tubes without in any manner being received within the dome 72 or within the casing 70 and in the manner illustrated. Valved pipes 74 and 75 communicate with upper and lower portions of the casing 73 surrounding the tubes and said pipes are connected to the couplings 64 and 65. It will be observed that the valve 58 is interposed between couplings 64 and 65. The next two temperature and pressure reducers *h* shown at 8 and 9 are similarly constructed and valved pipes 76 and 77 communicate with the casing 73 thereof and with the couplings 62 and 63 for the unit shown at 8, while valved pipes 78 and 79 communicate with the casing 73 and couplings 60 and 61 for the unit shown at 9. A pipe 80, provided adjacent its ends with valves 81 and 82, communicates between the heater *g* and the casing 70 of the unit at 7. A pipe 83 communicates with the dome 72 and through a valve 84 with the bottom of the casing 70 of the unit at 8. A pipe 85 communicates with the dome 72 for the unit at 8 and through a valve 86 with the casing 70 for the unit at 9. A pipe 87 communicates with the dome 72 of the unit at 9 and thence through a valve 88 with the dephlegmator *j*. This dephlegmator may have therein the usual baffle plates, whereby various vapors may be segregated and passed through pipes arranged at different levels of said dephlegmator for further passage into the coolers *k* shown at 10 and 11. Of course, the number of dephlegmators and coolers may be varied in accordance with use and practice. Residue from the dephlegmator may be collected and passed through valved pipes 89 and 90. Valved pipe 90 leads to the cooler unit *k* shown at 13 while the valved pipe 89 is associated with the cross-head coupling 69. The pump *m* is in communication with the heater *g* through a valved pipe 91 and another pipe 92 communicates with the pump and with some source of fluid supply, which fluid is to be forced within the heater *g* by the said pump *m*. The character of the fluid which is forced by the pump *m* into the heater may be varied. For instance, petroleum distillate, natural gas, hydrogen, or other gases may be utilized. The purpose of the temperature and pressure reducers is to gradually reduce in consecutive steps, temperature and pressure of the vapor or fluid passed therein.

While I do not wish to be restricted in this invention to any particular temperature or pressure, it may be said that the fluid received within the heater *g* may be maintained at 1000°, more or less, F., and possibly pressures of 50 to 70, or less or more, atmospheres maintained therein. The petroleum distillates, natural gas, hydrogen, or other gases, are forced by the pump *m* into this heater and the high heat plus the high pressure is sufficient to cause these gases, distillates or the like, to combine with the fluid passed within said heater, either directly from the coil 16, or the residue from the expander *e*. Forcing

the natural gas, hydrogen, or the like into the residue oil from the first cracking or topping plant lowers the specific gravity of the oil and causes a further cracking operation. However, 5 in order to make the gas, latently formed by this method evaporate and then condense, it is necessary to gradually pass said gas through the temperature and pressure reducers *h*. Thus, the gaseous fluid is passed through the pipe 80 into 10 the temperature and pressure reducer *h* shown at 7. This temperature and pressure reducer is set for a certain pressure through the medium of the valve 82 which is of the expansion type, and this expansion valve works in the ordinary 15 manner, namely, to open when the pressure is reduced below a certain amount in the means *h* whereby further fluid may be admitted therein, and to close when the pressure therein exceeds a certain amount. This gaseous fluid will pass 20 upwardly through the pipe 71 and outwardly through the dome 72 into the pipe 83 where it is passed into the temperature and pressure reducer shown at 8. There is included within the line 83 a pressure reduction valve 84, similar to the valve 25 82. Again the sequence of operation takes place, and the gases pass through the pipe 85 into the temperature and pressure reducer *h* shown at 9, the admittance of which is controlled by the reduction valve 86. Thence, the gaseous fluid is 30 passed through the pipe 87 past the valve 88 into the dephlegmator *j*. During all this time, the fluid which has passed through the pipe 13 and which initially warms the crude oil within the preheater *d* is passed into the jacket 73 sur- 35 rounding the pipes 71. As this fluid is initially cooler than the gaseous fluid flowing through the pipe 71, a heat exchange will occur. It will be noted that this fluid may be forced through the jackets of each of the temperature and pressure 40 reducers by proper control of the valves 56, 57 and 58 in one instance to close the same, and opening the valves in the pipes 74 to 79 inclusive. Of course, the number of temperature and pressure reducers may be varied at will, as may like- 45 wise be varied the number of dephlegmators *j*. It will be noted that pipes are in communication with different levels of the dephlegmator *j* and the cooler units *k* shown at 10 and 11, whereby different fractions of gases which have been 50 condensed may be received within the tanks thereof. A gradual reduction of temperature and pressure is of course necessary in order to obtain the vapors and condensates desired and for good practice. The initial forcing under pressure of 55 the natural gas, hydrogen or other gases, into the residue within the heater, which has been passed therein from the expander, tends to lower the specific gravity of the oil therein, and quite obviously the processes which thereafter follow 60 and the number thereof will depend upon the gravity of oil finally desired. It is, of course, realized that if it is not desired to use the oil from the coil 16, as the circulating medium, other fluids could be used. Ordinarily, the heavy 65 residues received within the heater *g* contain asphalt and carbon in large quantities and by the method which has just been described, it is possible to effect the conversion of the asphalt and free carbon into light fractions. The con- 70 verted liquid is cooled down and the pressure

reduced to the extent that finally by the last reduction, the expanded product is at barometric pressure and the latently converted fractions developed into gasiform which can be rectified by the dephlegmators *j*, then separated and condensed in the coolers and tank devices *k*. The residue may be received in the tank *k* shown at 13 or passed into the pipe line 54 or mingled with the oil passed through the coil 16 as will be observed is possible due to the method of 10 interconnecting the different pipes (see cross-head union 60). The cooling down and reduction of pressure from temperature and pressure reducer to temperature and pressure reducer must always be governed by the principle that 15 the temperature within any cooler must be in relative relation to the end that the heaviest product of fluid therein shall have no tendency to vaporize in such cooler and the tendency to vaporize shall only commence at the last tem- 20 perature and pressure reducer, at which time the reduction tends to the barometric pressure. When the barometric pressure finally obtains, then all the fractions within the latently converted liquid will have vaporized. It is evident 25 that the liquid flowing through the pipe 54 into the first temperature and pressure reducer shown at 9 will be cooler than it will be subsequently and therefore the arrangement shown works advantageously to effect the result finally sought. 30

In the preceding description, a system of distillation is shown which answers to all the needs of a modern refinery. Even vacuum distillations can be attached, in connecting the system A with a high vacuum plant. In that case, the light 35 fractions, as gasoline and heavy naphtha, may be abstracted just as above described but then the residues should be delivered to the high vacuum plant. This has the great advantage that it allows the hot residues before they are injected 40 openly into the vacuum and distilling plant, to do the heating while passing through the coils embedded in the vacuum stills. The temperature of these residues at the end of the topping period might be 250° C., while the heaviest oil to be 45 abstracted under high vacuum might be no more than 125° to 150° C. In that case, the lubricants being distilled would not require a separate fueling.

I claim:

The method whereby fuel oil may be treated to produce more valuable hydrocarbon products, which consists in first fractionating a crude oil to remove the light weight constituents therefrom and leave a residue, treating the residue under a temperature of approximately 1000° F., 55 more or less, and a pressure of 50 to 70 atmospheres, and at the same time injecting into said residue a fluid selected from the group comprising hydrogen and natural gas and adapted to 60 combine with said residue, to form lower boiling hydrocarbons, and thereafter passing the products of the thus treated residue through a series of temperature and pressure reducing stages, 65 correlating the temperature and pressure in each stage so that the heavier portions of treated residue products do not vaporize therein, and in the last stage vaporizing the lower boiling hydrocarbon product of the treated residue.

ALBRECHT VON GROELING. 70
